his ATTORNEY

UNITED STATES PATENT OFFICE.

EDWARD L. DELANY, OF BROOKLYN, NEW YORK.

FLOOR AND CEILING PLATE FOR PIPES.

1,320,453.

Specification of Letters Patent.

Patented Nov. 4, 1919.

Application filed December 20, 1918. Serial No. 267,603.

To all whom it may concern:

Be it known that I, EDWARD L. DELANY, a citizen of the United States, residing in the city of New York, borough of Brooklyn, county of Kings, and State of New York, have invented a certain new and useful Improvement in Floor and Ceiling Plates for Pipes, of which the following is a specification.

10 The object of my invention is to provide a device of this class which may be put about a pipe where it passes through a floor or a ceiling without difficulty and by easy manipulation, and when so placed is locked 15 against removal. This object is accomplished by means of my invention wherein a two part plate is employed with the respective parts secured by means of springs and joints so that the springs cause the 20 joints to interlock.

Features of the invention other than those adverted to will be apparent from the following detailed description taken in conjunction with the accompanying drawings.

25 The drawings show the preferred, practical embodiment of the invention, but the form shown is to be considered as typical only of various specific forms in which the invention may be given expression.

30 Figure 1 is a perspective view of the improved plate when positioned in place on a floor and around a pipe;

Fig. 2 is a plan view of the inner surface of the plate, ready for attachment to a pipe;

35 Figs. 3 and 4 are perspective views showing the respective members of the plate.

The improved plate 1 may be placed on a floor 2 or a ceiling where the pipe 3 enters or leaves. The plate is composed of two 40 members 4 and 5 which may be given any suitable form, and are so shaped at the inner edges as to snugly encircle a pipe, or substantially so, when in use, as shown in Fig. 1. These parts, which may be made

45 more or less ornamental, are provided with an inner collar 6 from which extend spring ears or lugs 7 which are located near the respective latches 8 and 9 of the parts 4 and 5. As many ears 7 may be employed as

50 desired, although in the preferred embodiment of my invention only two are used on each member and are preferably positioned close together as shown. It is desirable that they be placed near an end of each part and

55 not at or near the center for the reason which will appear below.

Each of the members 4 and 5 is provided with a socket 10, positioned on the concealed face of the plate and adapted to receive a latch. The latches are preferably of the construction described. Latch 8 is set off slightly so as to properly register with its socket as shown at 11, and then is flat, and preferably slightly tapering, and is so positioned as to lie parallel to the main portion 65 of the plate, said latch being provided with two notches 12 and 13 on its exterior edge. The notch 12 is so placed and shaped that the edge 14 may be struck from this notch as a center so that when the end of the latch 70 8 is inserted in the socket 10, this socket may be swung on the notch as a center without lost motion, until the latch 9 engages its socket 10. The latch 9 is offset at 15 and provided with one notch 16 and it is preferably tapered so as to readily engage its socket 10 and fit easily within the same. After the member 5 has been swung radially on the notch 12 as a center and the latch 9 brought into proper engagement 80 with its socket 10, the two parts 4 and 5 are shoved directly together until the notches 13 and 15 are opposite their places in the sockets 10. Then the springs 7 press against the pipe 3 and automatically, and without 85 further manual movement, force these notches laterally into engagement with the sockets, whereby the latches and sockets are positively engaged and the plate is held firmly and correctly in position. A reverse 90 movement unlocks and separates the parts of the plate. Once the parts have been centered about the pipe, as described, the plate is put in position with the tongues 7 between the pipe and floor or ceiling, as the 95 case may be. This structure holds the parts in place with a positive engagement which will not become loose or detached while in service and yet may be readily removed, when desired, by the simple manipulation 100 above described.

Slight changes may be made in the structure described, such as the substitution of equivalents, without departing from the spirit or substance of the invention, the 105 scope of which is commensurate with the appended claims.

Having thus fully described the invention, what I claim as new and desire to secure by Letters Patent, is:

1. A floor and ceiling plate, composed of two members each of which is provided with

laterally extended spring tongues adjacent to one end, sockets and latches, the sockets being so arranged and disposed as to inter- 5 engage with said latches when the parts are secured together and said latches being provided with notches, one having two notches and the other one, the said parts being so arranged and disposed that when the parts are secured together, one notch and a cor- 10 responding socket are first inter-engaged and then the parts swung on this notch as a pivot, until both latches and sockets are connected and then the parts are brought together with a direct movement and then shifted laterally until the parts are securely locked.

2. A device of the class described embodying two semi-cylindrical plates each of which is provided at one end with a socket 20 and at its other end with a notched latch, one of which latches has two notches, whereby one of the notches may be engaged with the socket of the other plate and the plates pivoted into opposed relation, whereupon 25 movement of the plates directly toward one another causes the second notch of the two notched latch to engage with its comple-

mentary socket and the notch of the other latch to engage with its complementary socket, and means for thereafter causing 30 relative lateral shifting to lock the latches within the sockets.

3. A device of the class described embodying a semi-cylindrical plate provided at one end with a socket and at its other end 35 with a notched tongue, a second semi-cylindrical plate provided at one end with a socket and at its other end with a notched tongue, said plates being adapted to be brought into position wherein the notched 40 tongue of the first plate engages with the socket of the second plate and the plates thereafter pivotally moved toward one another until the notched tongue of the second plate enters the socket of the first plate, 45 whereupon movement of the plates directly toward one another causes the plates to engage with one another and subsequent relative lateral movement of the plates results in locking coaction between the notches and 50 the sockets.

In testimony whereof, I have signed my name to this specification.

EDWARD L. DELANY.
